(57) **CLAIM**

The ornamental design for an LED source for a light fixture, as shown and described.

DESCRIPTION

FIG. 1 is a top view of a first LED source for a light fixture of the present design;

FIG. 2 is a front view of the LED source for a light fixture of FIG. 1;

FIG. 3 is a left view of the LED source for a light fixture of FIG. 1;

FIG. 4 is a right view of the LED arrangement of FIG. 1;

FIG. 5 is a rear view of the LED source for a light fixture of FIG. 1;

FIG. 6 is a bottom view of the LED source for a light fixture of FIG. 1;

FIG. 7 is a top view of a second LED source for a light fixture of the present design;

FIG. 8 is a front view of the LED source for a light fixture of FIG. 7;

FIG. 9 is a left view of the LED source for a light fixture of FIG. 7;

FIG. 10 is a right view of the LED arrangement of FIG. 7;

FIG. 11 is a rear view of the LED source for a light fixture of FIG. 7; and,

FIG. 12 is a bottom view of the LED source for a light fixture of FIG. 7.

Any parts shown in broken lines form no part of the claimed design.
